UNITED STATES PATENT OFFICE.

JAMES PALMER, OF PHILADELPHIA, PENNSYLVANIA.

BASS-KEY MECHANISM FOR ACCORDIONS.

Application September 22, 1922. Serial No. 539,896.

To all whom it may concern:

Be it known that I, JAMES PALMER, a citizen of the United States, residing at Philadelphia, in the county of Philadelphia and 5 State of Pennsylvania, have invented certain new and useful Improvements in Bass- Key Mechanism for Accordions, of which the following is a specification.

My invention relates to piano accordion 10 and more particularly to bass key mechanism therefor.

The object of the invention is to provide an improved bass key mechanism and mounting therefor, which will permit the removal of 15 the keys or buttons individually or simultaneously whereby to facilitate the assemblage, dissemblage replacements or repairs of the parts; to permit adjustment of the mounting for the working parts to fit casing sections of different sized instruments; to improve the mounting and connection of the valves and means for holding the valves closed, and to generally improve, simplify, enhance and facilitate the manufacture of 20 devices to which the invention appertains.

This object, and other advantageous ends which will be described hereinafter, I attain in the following manner, reference being had to the accompanying drawings in 30 which—

Figure 1 is a plan view of a casing section and bass key mechanism of a piano accordion, in accordance with the invention,

Figure 2 is a transverse sectional elevation taken on the line 2—2 of Figure 1,

Figure 3 is a transverse sectional view taken on the line 3—3 of Figure 1,

Figure 4 is a fragmentary detail perspective view of a portion of the mounting for 40 the bass key mechanism,

Figure 5 is a detail sectional view taken on the line 5—5 of Figure 1,

Figure 6 is a detail sectional view taken on the line 6—6 of Figure 1,

Figure 7 is a fragmentary plan view showing a set of valves and their mountings, and

Figure 8 is a transverse section of one of the valves taken on the line 8—8 of Figure 3.

Referring to the drawings, 1 indicates the 50 usual bellows of an accordion and 2 the casing for housing the bass key mechanism. Casing 2 is preferably cast of light metal, such as aluminum, and has a partition 3 integral therewith and provided with rows of holes 4 preferably arranged in single and double rows. Casing 2 is also provided with

a flange 5 to which bellows 1 is connected. Reed holders 6 are secured to partition 3 over holes 4 and are provided with walls 7 forming air pockets which communicate 60 with holes 4. Reeds 8 are mounted over the pockets in the usual way.

The edge of casing 2 is provided with a shoulder 9 to receive an ornamental cover plate, not shown, which is preferably of fret 65 work, to permit the emission of sound. The front corners 10 of the casing are spaced and provided with sloping inner faces 11 so that a key plate 12 may be disposed in the space between the corners and engage the 70 sloping faces 11 as shown in Figures 1 and 3. Keys 13, preferably cast of aluminum, are movable through plate 12.

The mounting for the bass key mechanism includes a support composed of longitudinal bars 14 and 15 connecting a pair of brackets 16 at their ends. Each bracket is provided with pads 17 removably secured to partition 3, an adjustable extension 22 having an inclined strip 18 to which key plate 12 is detachably secured and a rail 19 having recesses 20 in its inner face. The rail 19 on one of the brackets is provided with a removable section 21 to allow the parts fitting in the recess to be removed. 85 The adjustable extension 22 is channeled to slide on rail 19. A slot 23 is formed in the channeled part of extension 22 for receiving fastening screws 24 whereby the extensions may be adjusted lengthwise to 90 fit different sized accordions, and collapsed so as to be readily removed. An angular brace 25 connects each adjustable extension 22 with the ends of bar 14 to make them a unitary structure. An upright 26 95 is provided at the end of each rail 19 and a slightly larger upright 27 between the ends thereof, the upper end of each upright being slotted. An upright strip 28 is provided on removable section 21 to facilitate its removal and application and is secured to upright 27 by a screw 29. Extension 22 is recessed at 30 to provide clearance for section 21 when removing the same as shown in Figures 1, 4 and 5.

The bass key mechanism includes plunger bars 31 and 32, disposed in the slotted ends of uprights 26 and 27 and grooved to slidably receive plungers 33 which have the keys 13 cast on their ends. Strips 31' and 32' are secured to bars 31 and 32 over their grooves to prevent plungers 33 therein from

2 accidentally getting out of the grooves during their sliding movement. Pivot bars 34, made of metallic tubes, are mounted in recesses 20. A center support 35 is attached 5 to bar 15 and surrounds the pivot bars 34, as indicated at 36, to hold them in position in conjunction with recesses 20. Pivot bars 34 have arms 37 extending toward plungers 33 and engaging pins 38 on the 10 plungers. Pivot bars 34 are also provided with inclined arms 39 having bent ends extending toward the front of casing 2. Valves 40 and 40', cast of aluminum, are disposed over holes 4 and are supported on 15 valve arms 41 and 41' made of bent wire and pivoted to bar 14 by means of screws as shown at 43. Arms 41 and 41' are each bent and secured to valves 40 and 40' by screws 44, then extended outward at right angles to the valves as indicated at 45, and then in the direction of the length of the valves, as indicated at 46, and over the bent 20 ends of inclined arms 39. Springs, having arms 47 and 48, are fixed to bar 14 and exert pressure on valves 40 and 40' by engaging with parts 49 fixed to the valves to hold them closed.

Upon pressing a bass key 13 in the usual 30 way of playing a piano accordion, plungers 33 will be moved inward, arms 37 swung on their pivot bars 34 and arms 39 swung against parts 46 of arms 41 and 41', to raise and open valves 40 and 40' against the action of spring arms 47 and 48.

35 Upon releasing the pressed key, spring arms 47 and 48 will move the valves and their associated parts into their closed position again.

To remove the bass key mechanism, 40 screws 24 are loosened and extension 22, having key plate 12 thereon, slid toward the brackets. This movement brings plate 12 away from faces 11 and collapses the brackets into a smaller unit so that it may be readily removed from the casing. The 45 fastening means of pad 17 are then removed and the entire bass key mechanism, including the valves operated thereby, are then removed through the open end of the casing.

50 To remove the pivot bars 34, screw 29 is removed and section 21 lifted as shown in Figure 5 to allow one end of each pivot 34 to be removed from recesses 20.

To remove a plunger, strips 31' and 32' 55 are removed from grooved bars 31 and 32 and the plungers within the grooves then removed.

A bass key mechanism constructed as 60 above set forth facilitates the assemblage of the parts and disassemblage for repairs, is adjustable to fit different sized accordions, and will not warp, deteriorate or become loose jointed so as to effect the playing of the instrument.

65 While I have described my invention as

taking a particular form, it will be understood that the various parts of my invention may be changed without departing from the spirit thereof, and hence I do not limit myself to the precise construction set 70 forth, but consider that I am at liberty to make such changes and alterations as fairly come within the scope of the appended claims.

Having thus described my invention, 75 what I claim as new and desire to secure by Letters Patent is:—

1. In an accordion, a bass casing having a 80 partition; sound making means mounted on the partition; a support removably mounted on the partition; a key plate secured to the support, and bass key mechanism for controlling the sound making means mounted on the support and having its keys passing through the plate whereby the support and key plate may be removed with the bass mechanism as a unit.

2. In an accordion; a bass casing having a 85 partition; sound making means mounted on the partition; a support removably mounted on the partition, and provided with adjustable extensions; a key plate secured to the extensions, and bass key mechanism, for controlling the sound making 90 means, mounted on the support and having its keys passing through the plate, whereby the support and key plate may be collapsed 95 and removed with the bass mechanism as a unit.

3. In an accordion, a bass casing having a 100 partition and sloping faces adjacent its front side; sound making means mounted on the partition; a support removably mounted on the partition and provided with adjustable extensions; a key plate secured to the extensions and engaging the sloping faces, and bass key mechanism for controlling the sound making means mounted on the support and having its keys passing 105 through the plate, whereby the support and key plate may be collapsed to clear the sloping faces and removed with the bass key mechanism as a unit.

4. In an accordion, a bass casing having 110 a partition; sound making means mounted on the partition; brackets removably mounted on the partition; bars connecting the brackets, and bass key mechanism, for controlling the sound making means, 115 mounted on the brackets and the bars, whereby the brackets, bars and bass key mechanism may be removed as a unit.

5. In an accordion, a bass casing having 120 a partition; sound making means mounted on the partition; brackets removably mounted on the partition; bars connecting the brackets to form a unitary structure; valves for controlling the sound making 125 means pivoted on one of the bars, and bass 130

key mechanism, for controlling the valves, mounted on the brackets, whereby the brackets, bars, valves and bass key mechanism may be removed as a unit.

- 5 6. In an accordion, a bass casing having a partition; sound making means mounted on the partition; brackets mounted on the partition; bars connecting the brackets to form a unitary structure; valves pivoted on the bars for controlling the sound making means; springs mounted on the bars for keeping the valves in their closed position, and bass key mechanism, for controlling the valves, mounted on the brackets, whereby the brackets, bars, valves, springs and bass key mechanism may be removed as a unit.
- 10 7. In an accordion, a bass casing having a partition; sound making means mounted on the partition; brackets removably mounted on the partition, each bracket being provided with uprights; means connecting the brackets to form a unitary structure; plunger bars mounted on the uprights; plungers slideable in the bars; keys on the plungers; a key plate mounted on the brackets for slidably supporting the keys, and means for controlling the sound making means mounted on the brackets and operatively connected to the plungers, whereby the brackets and the above named parts connected therewith may be removed as a unit.
- 15 8. In an accordion, a bass casing having a partition; sound making means mounted on the partition; brackets removably mounted on the partition, each bracket being provided with recesses and uprights; means connecting the brackets to form a unitary structure; plunger bars mounted on the uprights; plungers slideable in the bars; keys on the plungers; a key plate mounted on the brackets for slidably supporting the keys; pivot bars mounted in the recesses; arms on the pivot bars operatively connected with the plungers; inclined arms on the pivot bars having bent ends; valves for controlling the sound making means, and means operatively connecting the inclined arms with the valves whereby the brackets and the above named parts connected therewith may be removed from the casing as a unit.
- 20 9. In an accordion, a bass casing having a partition; sound making means mounted on the partition; brackets removably mounted on the partition; an extension, having an inclined strip, slideable on each bracket; a key plate secured to the inclined strip, and bass key mechanism for controlling a sound

making means mounted on the brackets and 60 key plate, whereby the brackets and above named parts connected therewith may be removed as a unit.

- 10 10. In an accordion, a bass casing having a partition; sound making means mounted 65 on the partition; a support removably mounted on the partition and having uprights; bars mounted on the uprights; plungers slideable in the bars; keys on the plungers; a key plate mounted on the support for slidably supporting the keys; valves for controlling the sound making means, and means on the support operatively connecting the valves with the plungers, whereby the support and the above named 70 parts connected therewith may be removed as a unit.

- 11 11. In an accordion, a bass casing having a partition; sound making means mounted 75 on the partition; a support removably mounted on the partition and having uprights, the upper ends of the uprights being slotted; grooved bars mounted in the slots of the uprights; plungers slideable in the grooves of the bars; keys on the 80 plungers; a key plate mounted on the support for slidably supporting the keys; valves for controlling the sound making means, and means on the support operatively connecting the valves with the 85 plungers, whereby the support and the above named parts connected therewith may be removed as a unit.

- 12 12. In an accordion, a bass casing having 90 a partition; sound making means mounted 95 on the partition; a support removably mounted on the partition and having uprights; bars mounted on the uprights; plungers slideable in the bars; keys on the 100 plungers; a plate mounted on the support for slidably supporting the keys; pivot bars mounted on the support; arms on the pivot bars operatively connected with the plungers; inclined arms on the pivot bars having bent ends; valves pivoted on the support for controlling the sound making means, and valve arms on the valves extending over the bent ends of the inclined arms, whereby the support and the above 105 named parts connected therewith may be removed from the casing as a unit.

In testimony whereof I have signed my name to this specification in the presence of two subscribing witnesses.

JAMES PALMER.
